KEY FASTENER

Isaac F. Lumb and Howard T. Clasen,
Glenolden, Pa.

Application January 21, 1933, Serial No. 652,809

5 Claims. (Cl. 70—65)

Our invention relates to improvements in a key fastener, for holding a key against rotation or displacement relatively to the lock.

The object of our invention is to provide a novel 5 key fastener which will hold a key from being rotated within the lock, or removed from the lock by force applied to the key from the outside of the door.

A further object is to provide a key fastener 10 which may be readily attached and detached.

A further object is to construct a key fastener comprising two relatively movable members, with a spring interposed, for yieldingly holding the members in key engaging position, and making 15 the fastener adaptable for locks of different sizes.

A further object is to construct the members of 20 the key fastener with novel means for holding them from rotating relatively to each other, thereby insuring the members always being held in the proper position for attachment to a lock.

A further object is to form the members of wire, 25 each member comprising a straight body portion and loops, or bearings, in which the straight portion of the opposite member is slidably mounted.

A further object is to provide a key fastener 30 which is simple in construction and which may be manufactured at a low cost.

These together with various other novel features of construction and arrangement of the 35 parts, which will be more fully hereinafter described and claimed constitute our invention.

Referring to the accompanying drawing, Fig. 1 is a view in elevation showing our improved 40 key fastener.

Figure 2 is a plan view of Fig. 1.

Figure 3 is a horizontal section on line 3—3 of Fig. 1.

Figure 4 is a view in elevation showing the edge of a door and lock, and showing the key 45 fastener attached.

Figure 5 is a side view of Fig. 4, partly in section.

In the accompanying drawing in which like 50 reference characters refer to like parts, 10 represents our novel key fastener, comprising two members 12 and 13. Said members consist of straight body portions 14 and 15 and fastening devices, in the form of hooks 16 and 17, respectively.

The members 12 and 13 are preferably formed 55 of wire of sufficiently heavy gage to insure the members retaining their forms as shown in the drawing.

The members 12 and 13 are provided with bearings, or loops 18 and 19, formed upon the inner 60 ends of the body portions 14 and 15. The straight body portions 14 and 15 over-lap each other and

the loop 18 is slidably mounted on the straight body portion 13 and the loop 19 is slidably mounted upon the straight body portion 14.

The bearings, or loops 18 and 19 are each located with its axis off-set from the longitudinal 65 axis of the body portion on which the loop is mounted, thereby holding the body portions in spaced relation to each other.

A coiled spring 20 is positioned between the loops 18 and 19 and embraces one of the body 70 portions. Said spring tends to force the loops 18 and 19 apart, and thus slide the members relatively to each other so as to draw the hooks 16 and 17 toward each other.

A second loop 22 is provided upon the body 75 portion 14 of the member 12. Said loop 22 is positioned between the hook 16 and the loop 19 of the opposite member 13. Said loop 22 forms a stop which takes against the loop 19 and limits the distance the members may be moved by the 80 action of the spring 20.

The member 13 is provided with an extension 85 23, which is positioned in alignment with the body portion 15 and located upon the opposite side of the loop 19 relatively to the hook 17 on the member 13. The extension 23 occupies the loop 22 on the member 12 and slides loosely in the loop 22.

By providing one of the members with a plurality of loops, such as the loops 18 and 22 on the member 12, the members are held in parallel 90 relation to each other and by locating the loops eccentrically, or off-set, relatively to the longitudinal axis of the body portions on which they are mounted, the members are prevented from rotating relatively to each other, thus insuring the hooks 16 and 17 being held against relative rotation which greatly facilitates in applying the key fastener to the lock of a door.

The wires forming the hooks 16 and 17 are 95 folded upon themselves to form finger grips 25 and 26, for use in extending the members against the action of the spring 20 when attaching the key fastener to a lock.

Figures 4 and 5 show a portion of a door 28 and 100 a lock 30, having a latch 31 operated by the shank 32 and the door knob 33. A bolt 35 is operated by a key 36 when the latter is rotated. The key is held against rotation by our novel key fastener, by placing the hook 16 around the shank 105 32, or any other means of attachment which may be provided upon the door. The hook 17 is inserted through the handle of the key for holding the key against rotation, or from being removed 110 from the lock, by passing an instrument through

the key hole from the opposite side of the door. The spring 20 will yield and allow the members 12 and 13 of the key fastener to be extended sufficiently to allow the fastener to be applied to 5 locks of different sizes.

Various changes in the construction and arrangement of the parts may be made without departing from our invention.

We claim:—

- 10 1. A key fastener comprising two members each having a straight body portion, said body portions over-lapping each other, a loop upon each member, said loops occupied by the straight body portions of the opposite members and in which 15 loops said body portions are slidably mounted, a second loop upon one of said members in which second loop a portion of the opposite member is slidably mounted, a hook upon the outer end of each member, and a spring positioned between 20 the loops of the opposite members tending to urge said hooks toward each other.
2. A key fastener comprising two members each having a straight body portion, said body portions positioned in spaced parallel relation to each 25 other, a bearing upon one of said body portions, a plurality of bearings upon the other one of said body portions, said body portion upon one member being slidably mounted in the bearings upon the opposite member, said bearings positioned eccentrically relatively to the longitudinal 30 axis of the body portions on which they are mounted and arranged to prevent said members from rotating relatively to each other, fastening devices upon the outer ends of said body portions, and a spring positioned between the bearings of 35 the opposite body portions tending to urge said fastening devices toward each other.
3. A key fastener comprising two wire members each having a straight body portion, said body 40 portions of the opposite members positioned in spaced parallel relation to each other and over-lapping each other, a loop upon each body portion in which loop the body portion of the opposite member is slidably mounted, hooks upon the 45 outer ends of said members relatively to the loops, a second loop upon one of said body portions and embracing the straight body portion of

the opposite member, said loops positioned eccentrically relatively to the longitudinal axis of the body on which they are mounted and arranged to prevent said members from rotating relatively to each other, and a spring positioned between the loops of the opposite members tending to urge said hooks toward each other.

4. A key fastener comprising two wire members each having a straight body portion, said body portions of the opposite members positioned in parallel relation to each other and over-lapping each other, a loop upon each member embracing the over-lapping portion of the opposite body portion, a spring embracing one of said body portions and positioned between said loops tending to urge the loops apart, a hook upon the outer end of each member, a second loop upon one of said body portions, an extension upon the opposite body portion occupying said second loop, and said loops positioned with their axes eccentric to the longitudinal axis of the body portion on which the loops are mounted and arranged for preventing the rotation of the members relatively to each other.

5. A key fastener comprising two wire members each having a straight body portion, said body portions of the opposite members positioned in spaced parallel relation to each other and over-lapping each other, a loop upon each body portion in which loop the body portion of the opposite member is slidably mounted, hooks upon the outer ends of said members relatively to the loops, a spring embracing one of the body portions, said spring positioned between said loops and tending to urge the loops apart, a second loop upon one of said body portions, said second loop located between said first mentioned loops and the hook on the body portion on which the second loop is mounted and arranged to form a stop to limit the movement of said members by the action of the spring, and an extension upon the inner end of the opposite body portion relatively to the body portion on which said second loop is mounted, and said extension slidably mounted in said second loop.
